 tion of Michigan

Application May 4, 1936, Serial No. 77,723

27 Claims. (Cl. 200—83)

This invention relates to devices for making and breaking electrical circuits and more particularly to electric switches automatically operable in response to variations in an exterior condition 5 such as pressure, temperature, liquid level, etc.

One object of the invention is to provide an improved contact operating mechanism for an electric switch providing a quick make and break operation.

Another object of the invention is to provide improved means for calibrating an automatic electric switch including a calibrating spring acting on the pressure responsive element and which may be provided as part of a bellows assembly.

Another object of the invention is to provide means for establishing a relatively permanent limiting setting for the differential at which the switch operates.

Another object of the invention is to provide an improved form of differential adjustment for an automatic electric switch.

Another object of the invention is to provide an overload relay for an automatic electric switch which operates directly upon the contact actuating mechanism of the switch and which may be readily detached as a unit from the switch without disturbing its normal operating mechanism.

Another object of the invention is to provide an improved form of current responsive overload 30 for an electric switch.

Another object of the invention is to provide an improved unit assembly of current responsive overload relay, manual operating means and relay resetting means for an automatic electric switch.

Another object of the invention is to provide an electric switch including pressure responsive means for normally actuating the switch, auxiliary pressure responsive means for actuating 40 switch and manual and/or current responsive means for actuating a switch.

Another object of the invention is to provide means for sealing a slot in the switch housing which receives means for indicating the range 45 adjustment of the switch.

Other objects and features will be readily apparent to those skilled in the art from the following specification and the appended drawings illustrating certain preferred embodiments of the invention in which:

Figure 1 is a front elevational view of one form of an electric switch according to the present invention.

Figure 2 is an enlarged view similar to Figure 1

with the front cover plate removed and parts broken away to show internal parts.

Figure 3 is a vertical sectional view taken on the line III—III of Figure 2.

Figure 4 is a vertical sectional view taken on the line IV—IV of Figure 2.

Figure 5 is a horizontal sectional view taken on the line V—V of Figure 2.

Figure 6 is a partial sectional view taken on the line VI—VI of Figure 4.

Figure 7 is a partial view similar to Figure 2 with the contacts separated by the high pressure operated mechanism.

Figure 8 is a partial view similar to Figure 2 with the contacts separated by the normal pressure operated mechanism.

Figure 9 is a front elevational view of a different form of front cover where the switch includes thermal overload and manual operating means.

Figure 10 is a partial front elevational view 20 similar to Figure 9 with the cover removed.

Figure 11 is a horizontal sectional view taken on the line XI—XI of Figure 9.

Figure 12 is a partial view similar to Figure 10 but showing the contacts separated manually.

Figure 13 is a detail sectional view taken on the line XIII—XIII of Figure 10.

Figure 14 is a top plan view of a modified form of adjusting means.

Figure 15 is a vertical sectional view of the 30 switch shown in Figure 14.

Figure 16 is a fragmentary detail view showing the connection of the device for normal actuation in the reverse direction than that shown in the previous figures.

The switch illustrated in Figures 1 to 8, inclusive, comprises a housing 1 including a removable front cover 2. The housing is provided with various openings for the reception of conduit connector 3, normal pressure responsive actuating means 4 and means responsive to predetermined maximum pressure setting 5. The interior of the housing includes a projecting portion 6 against which is secured a U-shaped magnetic piece 7 by means of a conducting plate 8 insulated from the magnet by a sheet of fibre or other material 9. The plate 8 may be releasably held in position by a stud 11 which may thread into the plate. A bent up portion 12 may be provided at the front edge of the plate 8 to provide a terminal connector. A bent up portion 13 is provided at a back edge of the plate 8 for connection to the leaf spring 14 as by means of the stud 15. The leaf spring 14 carries a stationary contact 16 and is adjustably maintained in position by 55

bearing against the cam surface 17. This cam surface is preferably formed of insulating material and may be integral with an accessible portion 18 having an opposite reduced end portion 19 projecting through an opening in the plate 8 to provide a bearing. The accessible portion 18 may be provided with a slot for the reception of a screwdriver or other means for rotation of the cam surface 17. The cam surface is provided with a projecting portion 21 and the housing carries an adjusting screw 22 as a means for a relatively permanent setting preferably at the factory for the minimum differential to which the ordinary adjusting means can set the switch. 15 The enlargement 21 strikes the screw 22 in its clockwise movement, as seen in Figure 5 to limit the movement of the stationary contact 16 toward the right and hence the minimum differential for the switch as will be more fully explained 20 hereinafter.

To the bottom of the housing is rigidly secured a U-shaped supporting bracket 23 by means of studs 24. The opposite upstanding legs of the bracket are each equipped with a pair of spaced 25 threaded openings, 25, 26. Studs 27 having shaft-like bearing portions at their ends are threaded into the opposite holes 25 and project into bearing openings 28 in a pair of separately movable switch arms 29 and 31. These switch arms may carry 30 openings 32 for cooperation with the openings 26 in the supporting bracket in a manner to be hereinafter described. These arms have generally flat substantial vertical portions equipped adjacent the bottom with overlapping flanges 33 and 34 in which the bearing openings 28 and 32 are located.

The arm 31 is formed of conducting material such as aluminum or brass and carries adjacent its upper end a movable contact 35. A reduced 40 connecting portion between the contact 35 and the arm 31 is loosely received within a slot 36 at the top of arm 29 and provides for limited relative movement between the arms. The arm 29 is formed of steel or other magnetic material and is 45 disposed closely adjacent the opposite poles of the magnet 1 in the closed position of the contacts as shown. A small tension spring 37 connected at one end to a stationary part on the bracket 23 and its other end to the arm 31 biases 50 this arm toward the contacts engaged position. A pin 38 connects the opposite flanges on the arm 29 and is adapted to be engaged by an insulating part 39 on a pivoted lever 41. A flexible lead 42 connects the arm 31 to the back leg of the 55 bracket 23 and the front leg of the bracket may be provided with a terminal portion 43 for the reception of a circuit conductor. A support 44 integral with the housing projects from the back wall thereof and provides a means for connection 60 of the cover plate. A wall 45 connects projection 44 to the top interior wall of the housing and a stop 46 is provided on this wall to limit the contact separated position of the switching arm.

The normal pressure responsive element 4 includes 65 an exterior casing 47 having a connection means 48 secured thereto providing access to the interior of the housing 47. Within the housing 47 is disposed a corrugated bellows portion 49 having a bottom plate 51 brazed or otherwise 70 secured thereto. The bellows portion 49 is rigidly secured at its upper end to an annular portion 52 which is in turn secured to the interior of the housing 47. An actuating pin 53 is secured to the bellows plate 51 and extends upwardly into the 75 switch housing. A washer 54 loosely surrounds

the pin 53 and is disposed on top of the annular portion 52. An adjusting nut 55 is threaded on the upper end of pin 53 and a calibrating spring 56 is disposed between the washer 54 and the nut 55 and tends to bias the pin 53 upwardly. The 5 end of the pin is provided with a bearing point 57 received within a corresponding impression in the lever 41. This lever is U-shaped in cross section as shown in Figure 3 and is pivoted to projections 58 on the interior of the housing by 10 means of a shaft 59.

Upon the upper side of the lever 41 is disposed a compression spring 61 having its upper end received in a slightly cup-shaped member 62 which is rigidly connected to a sleeve 63 threaded on an 15 adjusting screw 64 having its end accessible at the top of the casing and there provided with a screwdriver slot for rotation. The front and back of the cup-shaped member 62 are extended as at 65 and 66. The back extension 65 is prevented from rotating by a pair of spaced projections 67 on the back interior wall of the housing and this projection 65 is guided by the projections 67 for longitudinal movement in the adjustment of the range of operation of the device. To the 20 front extension 66 is rigidly secured a leaf spring 68 carrying an indicating pin 69 at a generally mid point. The front cover for the switch is provided with a slot 71 having indicia therealong and the pin 69 is adapted to indicate the adjustment of the device by its position adjacent these indicia. When the front cover is in place the spring 68 presses against the slot and serves to seal the opening of the cover. The length of the spring 68 is roughly twice that of the slot so that 25 when the pin is placed at a mid point the spring substantially closes the slot in both extreme positions of the pin corresponding to the extreme limits of adjustment. As the screw 64 is turned from the exterior of the housing, the threaded 30 sleeve 63 and the generally cup-shaped member 62 attached thereto will move downwardly and compress spring 61, thus changing the pressure exerted thereby upon the lever 41. A collar 72 on the end of the screw 64 is engaged by the sleeve 35 63 to limit the extreme compression of the spring 61. The screw 64 is provided with an upper collar 73 and a plate 74 is disposed against the inside 40 top of the housing to provide a bearing surface for this collar.

The insulating member 39 constitutes an extension on the lever 41, being rigidly secured thereto as by riveting. The upper surface of this member is provided with a projection 75 adapted to contact with a downward projection 76 on the 55 central support 44 to limit the upward movement of the lever 41. An extension 77 is provided on the inside bottom of the housing to limit the lower movement of the lever.

The portion of the switch which has now been 60 described constitutes the normal operating switching mechanism by which the movable contact automatically moves to engaged and separated position in response to a change in pressure within the bellows chamber. This much of the 65 device constitutes a complete switch in itself and the other apparatus shown in the drawings and to be later described constitutes an auxiliary device for operating the switch in response to a different condition. The operation of that portion of the 70 switch which has thus far been described will now be explained.

As shown in Figures 2, 4 and 6, the parts are in their closed circuit position. As shown in Figure 8, the parts are in their normal circuit open posi- 75

tion. The operation of the switch is dependent upon the resultants of the force exerted on the lever arm 41 by the range spring 61 and that exerted on this lever by the bellows pin 53. With the parts shown in Figures 2, 4 and 6, the pressure within the bellows chamber aided by the calibrating spring 56 is sufficient to overcome the force exerted on the lever arm by the range spring 61. If this pressure decreases the range 10 spring will move the lever 41 downwardly whereupon the insulating end portion 39 on the lever engages the pin 38 on the arm 29 and pulls it downwardly. When the moment of this force about the pivot of the arm is sufficient to overcome the moment of the attraction of magnet 7 on the arm 29, this arm will move in a clockwise direction. The first part of this movement does not separate the contacts as the construction provides for a limited relative movement between 15 the levers 29 and 31. As the arm 29 moves away from the magnet the force exerted thereby rapidly decreases so that by the time the arm 29 engages the arm 31 it will move the movable contact 35 to the disengaged position with a snap 20 action. These arms will then move together in a clockwise direction until they engage the stop 46 as shown in Figure 8. When in Figure 8, as the pressure within the bellows increases, the force exerted by the pin 53 from the bellows and the 25 calibrating spring 56 will overcome the force exerted by the spring 61 and the lever 41 will be moved upwardly, thus permitting arms 31 and 29 to move toward contacts engaged position under the bias of the spring 37. Before the contact 35 30 engages the stationary contact 16 the magnetic arm 29 will have approached within a substantial portion of the field of the magnet 7 whereupon the arm 29 will quickly pull the contact 35 into its engaged position so that the engagement 35 of the contacts will also occur with a snap action. It is to be noted that in the "on" position the magnetic arm 29 bears against the stationary contact 35 so that the contact pressure is supplied not only by the spring 37 but also by the force 40 exerted by the magnet on the arm 29. To adjust the range at which the switch operates the screw 64 is turned from the exterior of the casing, thus increasing or lessening the compression on spring 61 and thereby increasing or lessening the pressure 45 sure necessary to be exerted by the bellows element to cause motion of the lever 41. The calibrating spring 56 may be varied by removing the front cover and turning the knurled nut 55. This calibrating spring exerts a pressure on the bellows pin in the same direction as an increase in 50 pressure by the bellows and serves to provide an adjustment which may be used for factory calibration of the range. Thus, if the total range of the spring 61 is 50#, adjustment of the calibrating spring 56 will determine the point at 55 which the 50# range occurs. This calibrating spring further serves to provide for operation at a vacuum as when this spring is adjusted for tension greater than the range spring 61 the resultant force on the lever 41 is upward thus 60 requiring a vacuum or suction to move the lever 41 downwardly.

The differential adjustment provides means for varying the limits between the engagement 70 and disengagement of the contact. This is done by turning the element 18 whereupon the cam surface 17 varies the position of the stationary contact and by this varies the distance between the magnetic arm 29 and the magnet 7 in the 75 contacts engaged position. When the stationary

contact 16 is at its farthest position to the right as viewed in Figure 5, the magnetic gap will be greatest and the differential at a minimum. When the stationary contact is at its farthest position to the left, as viewed in Figure 5, the magnetic gap will be least and the differential at a maximum. The parts are assembled to have a given maximum setting of differential and the minimum setting is adjusted by the screw 22. It is obvious that the minimum setting could be 10 determined by assembly and the maximum setting adjusted by the screw 22 in the same manner.

In the switch illustrated in Figures 1 to 8, inclusive, there is included means for positively moving the contact 35 to its disengaged position 15 irrespective of the pressure on the bellows element 4. This device constitutes what is known as a high pressure cutout and includes a pressure responsive unit denoted generally at 5 having a bellows 10 carrying a pin 78. A compression 20 spring 80 is disposed around the pin and bears against the bellows to oppose its movement. An adjusting screw 90 of cylindrical form is threaded into a fixed part and bears against the upper end of the spring 80. The pin 78 slidably projects 25 through the screw 90 into a housing 79 carrying a supporting bracket 81 having a slot in its front face. A plate-like element 82 constituting one arm of an over center toggle has a pair of projections extending into the slot in the front face 30 of bracket 81 and its opposite edge is provided with a point connection 83 with a spring holding member 84. An opposite spring holding member 85 has a point connection 86 with an adjusting screw 87. A compression spring 88 is disposed 35 between the members 84 and 85. This spring simply constitutes the other arm of the over center toggle. A pin 89 extends upwardly into the switch housing and is biased against the plate 82 by a compression spring 91. A shaft 92 is provided between the opposite sides of the supporting bracket 23 and upon this shaft is pivotally mounted a lever 93 biased by a spring 94 in a counterclockwise direction. The lever 93 is provided with an arm 95 in the path of the pin 89.

The high pressure cutout is adapted to be connected to a controlling device such as a high pressure side of a refrigerator system and when the pressure reaches a predetermined maximum the force of the bellows pin 78 will snap the toggle formed by the arm 82 and the spring 88 into its over center position, thus snapping the pin 89 quickly in an upward direction. The upper end of the pin 89 then engages the arm 95 on the lever 93 and moves into position shown in Figure 7, wherein the end of the lever has engaged arm 29 and thus positively moved the contact 35 to the disengaged position. If the pressure within the bellows 5 thereafter decreases until it is no longer sufficient to hold the toggle in its over center position the toggle will snap over and the pin 89 will permit the lever 93 to move to its original position under the bias of spring 94. When this happens the contact will again be under the control of the normal operating mechanism.

It is to be noted that in thus opening the contacts the high pressure cutout does not in any case have to be operated against the pressure exerted by the bellows 4 or the spring 61 as it is seen that the movement of the contact arms from engaged position tends to move the pin 38 away from the insulating portion 39 of the lever 41 and hence there is no counteracting of the action of the high pressure cutout by the normal operating mechanism. This is clearly seen by

an inspection of Figure 7 where if the bellows 4 is exerting a high pressure the lever 41 will be up and the contacts engaged and the lever 93 when operating to disengage the contacts will simply move the pin 38 away from the portion 39 of the lever 41. If on the other hand the lever 41 should be in a downward direction the contacts will already have opened and if the high pressure cutout is somehow operated the lever 93 will simply move until it engages the contact assembly in disengaged position. Adjustment of the range of the high pressure cutout is determined by the adjusting screw 81 which varies the force on the bellows 76. Adjustment of the differential of operation of the high pressure cutout is determined by the adjusting screw 81 which varies the tension exerted by the spring 88 and hence the force necessary to move it over center. A locking nut 96 may be provided on the screw 81 to prevent accidental adjustment thereof. For mounting the switch in place a metallic bracket 97 is mounted on the exterior back wall of the housing and projects beyond the ends thereof where it is provided with holes 98 for the reception of mounting screws. The support 44 is provided with a metallic insert into which the cover screw 99 may be threaded to secure the front cover into position.

For the sake of simplicity in the drawings, 30 the switch according to the present invention having thermal overload relay and manual operation has been shown separately in Figures 9 to 13, inclusive, and the normal operating mechanism and high pressure cutout have been only 35 partially shown. The thermal overload relay and the manual operating mechanism are mounted together on a unitary insulating base 101 and include a current responsive element of the solder pot type embodying a ratchet wheel 102 mounted on a shaft and normally held 40 against rotation by a solidified metal within the cylindrical container 103. A resistor coil 104 surrounds the container 103 and is serially connected in the circuit through the switch by 45 terminal screws 105 and 106. The terminal screw 106 is threaded into a conducting plate 107 carrying a terminal screw 108 for the reception of a circuit conductor. Terminal screw 105 is threaded into the terminal 12 previously described. To improve the electrical connection 50 between the end of resistor coil 104 and terminal 12 a U-shaped piece of copper or other conducting material 109 may be disposed about the corner of the base 101 so that one side of the conducting piece bears against the terminal 12 and the other side against the end of the resistor coil, the conducting parts being held in place 55 solely by the screw 105.

The base is provided with a slot 111 in which 60 is disposed a generally rectilinearly movable element 112 carrying a striker 113 on one end adapted to engage a projection 114 on the magnetic arm 29 in moving to the right as shown in Figure 13. Member 112 is provided with an 65 indicating extension 115 having a part disposed closely adjacent to the corresponding front portion of the switch housing cover and carrying indicating means disposed adjacent an opening 116 in the cover to show the tripped or set condition of the relay. The member 112 is furthermore equipped with a latching projection 117 70 adapted to engage with the teeth on the ratchet wheel 102 to hold the element 112 in its lefthand position as viewed in Figure 13. The member 75 112 is guided at its lefthand end within an open-

ing 118 in the base 101 and at its righthand end by a pin 119 spanning the slot 111 in the base 101. A spring 121 interconnects a stationary post on the base with the extension 115 and biases the member 112 for movement toward the right and also for rotation about the pin 119 as it is located considerably above the plane of the pin. This insures the latching of the projection 117 with the teeth of the ratchet and the movement of the member toward the right when released. With passage of an overload current through the switch the heat generated by the coil 104 will be sufficient to fuse the binding metal within the cylinder 103 whereupon the shaft holding the ratchet wheel 102 will be free 15 to rotate and the member 112 will be released for movement toward the right under the action of its biasing spring. This movement causes the striker 113 to engage the extension 114 on the arm 29 and moves the contact 35 to separated position. It is to be noted that this movement, similar to that caused by the high pressure cutout, is free from any resistance from the normal operating mechanism.

For manually moving the contacts to disengaged position and for resetting the thermal operation, a rotary shaft 122 pivotally extends through the base 101 and at the back of this base has an insulating striker arm 123 rigidly connected thereto. This striker arm is adapted 30 to engage a projection 124 on the arm 29 and move the contact 35 to separated position as shown in Figure 12.

At the front of the base 101 an arm 125 is also rigidly secured to the shaft 122 and is adapted 35 when rotated to contact with the member 112. A spring guide 126 is pivotally attached to a part connected to the arm 125 and a spring 127 is disposed thereon between the end of the guide and a stationary bracket 128 and is adapted to 40 be moved over center by rotation of the handle to secure accelerated movement for the manual operation. An elongated stud 129 is threaded into the support 44 to rigidly support the base in position. The cover screw 99 is then threaded 45 into the head of the stud 129 to hold the cover in position. Where the manual and overload are used the cover is provided with a box-like portion 131 to provide clearance for the base 101 and the mechanism mounted thereon. A 50 manual operating handle 132 is pivotally mounted on the cover and has a portion projecting therethrough ending in a tongue 133 received within a slot 134 in the shaft 122.

The operation of both the thermal overload 55 and the manual operator should be readily apparent. The circuit for the switch passes from the terminal 108 through the plate 107, through the resistor coil 104, through the terminal 105 and conducting strip 109 to the extension 12 on the plate 8 from which it passes through the extension 13 and the leaf spring 14 to the stationary contact 16, thence from the movable contact 35 through the arm 31 and the flexible lead 42 to the bracket 23 and the opposite circuit terminal 60 43. When the current through the switch is beyond the rating of the current responsive part of the thermal overload relays the heating from the coil 104 will fuse the metal within the container 103 and release the ratchet wheel 102, whereupon the member 112 will move to the right and the striker 113 engaging the extension 114 on the lever 29 will cause the movable contact 35 to move to its separated position. To reset the thermal overload the manual operating mem- 65 70 75 75

ber 132 is rotated clockwise, whereupon the arm 125 engages the member 112 and moves it to the left and into relatching engagement with ratchet wheel 102. If the metal in cylinder 103 has solidified the ratchet is held against rotation and member 112 will be latched in its reset position with the striker out of engagement with the extension 114. To manually open the contacts the manually operated member is rotated clockwise, whereupon striker 123 engages extension 124 and moves the movable contact 35 to the disengaged position. Rotation of the manually operated member 132 thereafter in a counterclockwise direction will move the striker 123 out of the path of the extension 124 and return the control of the movable contact to the normal operating mechanism. The position of the parts as shown in Figure 12 corresponds to manual "off" position and also to reset position for the overload relays. In the normal movement of the manual operator to "on" and "off" position, the movement is accelerated by the movement of the spring 127 over its dead center position. It is noted that in the resetting of the member 112 the arm 123 engages the extension 124 and prevents the contacts from returning to engaged position while the overload is disabled by being reset. After reset, the manually operated member is turned counterclockwise to place the control again in the normal operating mechanism. It is noted that the movement of the contacts to disengaged position by the thermal overload relay, by manual operation and by the high pressure cutout are all three accomplished without resistance from the normal operating mechanism and that while each of these three elements positively moves the movable contact to disengaged position, none of them positively moves it to engaged position but simply restores the control of the contact to the normal operating mechanism and permits this mechanism to move the contact to engaged position if its operating characteristics are so set. It is to be noted that while the manual operator and thermal overload relay both actuate the movable contact to disengaged position, these elements can be attached and detached as a unit without changing the normal operating mechanism. All that is necessary is to remove the stud 129 and screw 105 whereupon the base 101 and the entire manual and overload relay may be disassembled from the switch without disturbing the normal operating mechanism. This is a highly desirable feature as it provides obvious economies in substituting one relay unit for another and also provides for the ready attachment of a relay unit to an existing switch in the field. Due to the connection of the tongue 133 with slot 134 in the shaft 122 the cover may be readily removed from the switch without disturbing the unit assembly made up by the overload relay and manual operating mechanism other than to remove the exterior manual operating handle.

Figures 14 and 15 show a modified arrangement for securing adjustment of the differential and the range by means of exterior knobs rather than by the screwdriver adjustment heretofore described. In this connection, the screw 64 for adjusting the range is extended through the cover and a knob 135 is attached thereto by a set screw 136. In the differential adjustment the element 18 is extended beyond the cover and a knob 137 and an indicating scale 138 attached thereto by a set screw 139. In this construction the indicating scale 138 has a tongue 141 bent therefrom and disposed against a flat portion on the mem-

ber 18 whereupon the single set screw 139 serves to securely hold the knob and indicating scale on the shaft extension.

Figure 16 shows the arrangement of the parts for what is known as "direct" action. Here the 5 trunnion studs 27 have been threaded into the openings 26 in the supporting bracket 23 and project into the openings 32 in the arms 29 and 31 pivoting them at this point. The insulating end portion 39' on the lever 41 is in the reverse 10 direction and engages with the pin 38 when moved upwardly. The pin 38 is now at the left of the pivot point of the switching arms so that movement of this pin upwardly by an increase 15 in pressure in the bellows moves the contact to separated position. It is to be noted that in this changing from "reverse" to "direct" action the length of the lever arm 41 to the pin 38 remains the same and the distance between the pin 38 and the pivot point of the switching arms remains the same so that the operating forces will 20 be comparable as the moment arms through which they are applied are substantially the same.

While certain preferred embodiments of the 25 invention have been specifically disclosed, it is understood that the invention is not limited thereto as many variations will be readily apparent to those skilled in the art and the invention is to be given its broadest possible interpretation 30 within the terms of the following claims.

What is claimed is:

1. In an electric switch, a pair of generally parallel, rigid arms, each pivotally mounted on a relatively fixed part and each having limited relative movement independently of the other about its pivotal mounting on said part, a contact element supported on one of said arms, an opening in the other of said arms through which said contact element loosely extends, a stationary contact cooperating with said contact element to complete a circuit through the switch, and means for moving said other arm into engagement with said one arm to move said contact element to separated position.

2. In an electric switch, a pair of generally parallel, rigid arms, each pivotally mounted on a relatively fixed part and each having limited relative movement independently of the other about its pivotal mounting on said part, a contact element supported on one of said arms, a stationary contact cooperating with said contact element to complete a circuit through the switch, means biasing said one arm toward contacts-engaged position, a magnet element holding the other of said arms in said position, and means for moving said other arm against the force of said magnet to engage said one arm with a snap action and move it to contacts-separated position.

3. In an electric switch, a pair of generally parallel, rigid arms, each pivotally mounted on a relatively fixed part and each having limited relative movement independently of the other about its pivotal mounting on said part, a contact element supported on one of said arms, a stationary contact cooperating with said contact element to complete a circuit through the switch, means biasing said one arm toward contacts-engaged position, a magnet element attracting the other of said arms into said position, means limiting the movement of said other arm toward said magnet, and means for moving said other arm away from said magnet to move the contact element to separated position.

4. In an electric switch, a pair of generally parallel, rigid arms, each pivotally mounted on a relatively fixed part and each having limited relative movement independently of the other about its pivotal mounting on said part, a contact element supported on one of said arms, a stationary contact cooperating with said contact element to complete a circuit through the switch, means biasing said one arm toward contacts-engaged position, a magnet element attracting the other of said arms into said position, means limiting the movement of said other arm toward said magnet, and means for moving said other arm away from said magnet to move the contact element to separated position, said limiting means being adjustable to vary the differential at which the switch operates.

5. In an electric switch, a pair of generally parallel, rigid arms, each pivotally mounted on a relatively fixed part and each having limited relative movement independently of the other about its pivotal mounting on said part, a contact element supported on one of said arms, an opening in the other of said arms through which 20 said contact element loosely extends, a stationary contact cooperating with said contact element to complete a circuit through the switch, means biasing said one arm toward contacts engaged position, a magnet element attracting 25 said other arm into said position, and means on said contact element engageable by said other arm in said position to limit its position with respect to said magnet and to increase contact pressure, and means for moving said other arm 30 away from said magnet to move the contact element to separated position.

6. In an electric switch, a rigid switching arm pivotally mounted on a fixed part, a contact surface on said arm, a stationary contact cooperating 40 with said contact surface to complete a circuit through the switch, a magnetic element movable in the path of said arm independently thereof, spring means biasing said switching arm toward contacts engaged position, a magnet biasing 45 said magnetic element out of engagement with said arm to permit the contact and contact surface to be engaged under the action of said spring biasing means, and pressure responsive means for moving said magnetic element away 50 from said magnet to move the switching arm to contacts separated position.

7. In an electric switch, a rigid switching arm pivotally mounted on a fixed part, a contact surface on said arm, a stationary contact cooperating 55 with said contact surface to complete a circuit through the switch, a magnetic element movable in the path of said arm independently thereof, a magnet biasing said element out of engagement with said arm, and operating mechanism automatically responsive to exterior conditions for moving said element away from the magnet to move the arm to contacts separated 60 position and for moving said element and arm into their contacts engaged position.

8. In an electric switch, a rigid contact member pivotally mounted on a fixed part and movable to "off" and "on" positions, a magnetic element movable independently of said member and having a limited lost motion with respect thereto, spring means biasing said member toward "on" 70 position, a magnet biasing said element to a position corresponding to the "on" position of said member, and mechanism automatically responsive to an exterior condition for moving said 75

element away from said magnet to move the member to "off" position.

9. In an electric switch, relatively movable contacts, means responsive to an exterior condition for moving said contacts to separated and 5 engaged positions, a rotary cam for varying the differential in said condition between said opposite movements, an abutment connected with said cam, and an adjustable stop adapted to cooperate with said abutment to provide a relatively permanent setting of the extreme position to which said cam may be moved.

10. In an electric switch, stationary and movable contacts, a magnetic arm movable to move said movable contact to disengaged position, 15 means responsive to an exterior condition for moving said arm, a magnet biasing said arm against movement to contacts disengaged position, and means for varying the space between said arm and said magnet in the contacts engaged position to provide a differential adjustment, and means for adjustably limiting the maximum space obtainable by said space varying means.

11. In an electric switch, stationary and movable contacts, a magnetic arm movable to move said movable contact to disengaged position, mechanism responsive to an exterior condition for moving said arm, a magnet exerting a force tending to hold said arm in contacts engaged 30 position, the position of said arm with respect to said magnet being limited by the engagement of said contacts, a resilient mounting for said stationary contact, a cam surface for positively backing said stationary contact, and means for 35 moving said cam surface to vary the position of said stationary contact and the space between said arm and magnet in the contacts engaged position.

12. In an electric switch, stationary and movable contacts, a magnetic arm movable to move said movable contact to disengaged position, mechanism responsive to an exterior condition for moving said arm, a magnet exerting a force 40 tending to hold said arm in contacts engaged position, the position of said arm with respect to said magnet being limited by the engagement 45 of said contacts, a movable cam surface, a spring arm movable by said cam surface, the stationary 50 contact being mounted on said arm, whereby the space between said arm and magnet in the contacts engaged position may be varied.

13. In an electric switch, stationary and movable contacts, a magnetic arm movable to move 55 said movable contact to disengaged position, mechanism responsive to an exterior condition for moving said arm, a magnet exerting a force tending to hold said arm in contacts engaged position, the position of said arm with respect to said magnet being limited by the engagement 60 of said contacts, a resilient mounting for said stationary contact, a cam surface for positively backing said stationary contact, means for moving 65 said cam surface to vary the position of said stationary contact and the space between said arm and magnet in the contacts engaged position, and means for adjustably limiting the movement of said cam surface in its space increasing direction to set the minimum differential obtainable.

14. In an electric switch, stationary and movable contacts, a switching member movable to move said movable contact to engaged and dis- 75

- engaged positions, mechanism responsive to an exterior condition for moving said member and means responsive to the current through the switch for moving said member to contacts disengaged position, said means constituting a unit assembly readily detachable from the switching unit without disturbing its normal operating mechanism.
15. In an electric switch, stationary and movable contacts, a switching member movable to move said movable contact to engaged and disengaged positions, opposed resilient and pressure responsive means for moving said member, a magnet biasing said member toward contacts engaged position to provide contact make and break with a snap action, and means responsive to the current through the switch for moving said member to contacts disengaged position, said means constituting a unit assembly readily detachable from the switching unit without disturbing its normal operating mechanism.
16. In an electric switch, stationary and movable contacts, a switching member movable to move said movable contact to engaged and disengaged positions, a spring biasing said member toward contacts engaged position, a magnet biasing said member into contacts engaged position, opposed resilient and pressure responsive means for moving said member to contacts disengaged position, and a unit assembly readily attachable to and detachable from said switching unit without disturbing its normal operating mechanism and including current responsive means for moving said member to contacts disengaged position in response to an overload current through the switch.
17. In an electric switch, stationary and movable contacts, a switching member movable to move said movable contact to engaged and disengaged positions, mechanism responsive to an exterior condition for moving said member, means responsive to the current through the switch for moving said member to contacts disengaged position, manual means for moving said member to contacts disengaged position and for resetting said current responsive means, said means constituting a unit assembly readily attachable and detachable from the switching unit without disturbing its normal operating mechanism.
18. In an electric switch, a switching member, separable contacts controlled by said member, mechanism responsive to an exterior condition for normally automatically moving said member, a unit assembly overload relay detachably associated with said switch and having a striker biased to move said member to contacts separated position and current responsive latching means holding said striker against said bias.
19. In an electric switch, a switching member, separable contacts controlled by said member, mechanism responsive to an exterior condition for normally automatically moving said member, a unit assembly overload relay detachably associated with said switch and having a striker biased to move said member to contacts separated position and current responsive latching means holding said striker against said bias, a second striker manually operable to engage said member, and means connected with said second striker for moving said first striker into latched position after release.
20. In a unit assembly overload relay for an automatically operated switch, a base, a rectilinearly movable striker on said base, a spring biasing said striker, current responsive latching means for said striker, a pivoted, manually operable striker, and an element rigid with said pivoted striker for engaging and moving said first striker into latching position after release, the pivoted striker being in operating position when resetting said first striker.
21. In a unit assembly overload relay for an automatically operated switch, a base, a rectilinearly movable striker on said base, a spring biasing said striker, a solder pot latching wheel on said base for holding said striker against said bias, a series connected heater for said solder pot, a pivoted manually operable striker, and an element rigid with said pivoted striker for engaging and moving said first striker into latching position after release.
22. In a unit assembly overload relay for an automatically operated switch, a base, a rectilinearly movable striker on said base, a spring biasing said striker, a solder pot latching wheel on said base for holding said striker against said bias, a series connected heater for said solder pot, a pivoted manually operable striker, and an element rigid with said pivoted striker for engaging and moving said first striker into latching position after release, and an over-center spring connected with said pivoted striker for causing its non-latching movements to be snap-like in action.
23. In an electric switch, a switching member, separable contacts controlled by said member, means responsive to an exterior condition for normally moving said member to contacts engaged and separated positions, means responsive to an overload current condition for moving said member to contacts separated position, manual means for moving said member to contacts separated position, and means responsive to a predetermined maximum exterior condition for moving said member to contacts separated position.
24. In an electric switch, a switching member, separable contacts controlled by said member, pressure responsive means for normally moving said member to contacts engaged and separated positions, means responsive to an overload current condition for moving said member to contacts separated position, manual means for moving said member to contacts separated position, and means responsive to a predetermined maximum pressure for moving said member to contacts separated position, operation of each of said last three means predominating over any tendency for said first mentioned means to move the member to contacts engaged position.
25. In an electric switch, a switching member, separable contacts controlled by said member, a spring biasing said member to contacts engaged position, opposed resilient and pressure responsive means for moving said member to contacts disengaged position, current responsive means for moving said member to contacts disengaged position, manual means for moving said member to contacts disengaged position and means responsive to a predetermined maximum pressure for moving said member to contacts disengaged position, said spring moving said member to engage the contacts only when all four of said means are in inoperative position.
26. In an electric switch, a switching member, separable contacts controlled by said member, means responsive to an exterior condition for normally moving said member to contacts engaged and separated positions, manual means for moving said member to contacts separated position, and means responsive to a predetermined

maximum pressure condition for moving said member to contacts separated position.

27. In an electric switch, a switching member, separable contacts controlled by said member,
5 means responsive to an exterior condition for normally moving said member to contacts en-

gaged and separated positions, current responsive means for moving said member to contacts separated position, and means responsive to a pre-determined maximum exterior condition for moving said member to contacts separated position. 5

CARL A. SCHAEFER.
